UNITED STATES PATENT OFFICE.

HERBERT I. WILBER, OF DORCHESTER, MASSACHUSETTS.

ROTARY GAS-ENGINE.

973,833.

Specification of Letters Patent. Patented Oct. 25, 1910.

Application filed July 16, 1909. Serial No. 508,063.

To all whom it may concern:

Be it known that I, HERBERT I. WILBER, a citizen of the United States of America, and a resident of Dorchester, in the county of 5 Suffolk and State of Massachusetts, have invented certain new and useful Improvements in Rotary Gas-Engines, of which the following is a specification.

This invention relates to rotary gas engines and has for its object the production of a device of this class which will be economical in its operation while simple in construction.

It consists in an engine provided with a plurality of piston chambers, each of which has a separate compression chamber adapted to communicate with its own piston chamber, to be cut off therefrom, or to be placed in communication with another piston chamber during the various revolutions of the piston.

It consists in a device of this class in which a valved passage connects a plurality of piston chambers, the valves of which are operated to permit a charge in one piston chamber to be compressed by the action of the explosion behind said piston and after such compression to be transferred into another piston chamber and confined therein until the explosion therein takes place.

It consists further in a device of this class in which a plurality of piston chambers are used, so constructed and operated that a greater number of explosions occur in one piston chamber than in another.

It consists further in a novel construction of piston blade and means for operating it.

It consists further in certain novel features of construction and arrangement of parts which will be readily understood by reference to the description of the drawings and to the claims hereinafter given.

Of the drawings: Figure 1 represents an elevation of an engine embodying the features of the present invention. Fig. 2 represents a plan of the same. Fig. 3 represents a transverse section of the same, the cutting plane being on line 3—3 on Fig. 2, looking in the direction of the arrow. Fig. 4 represents a vertical section of the same, the cutting plane being on line 4—4 on Fig. 3, looking in the direction of the arrow. Fig. 5 represents a vertical section of a portion of the same, the cutting plane being on line 5—5 on Fig. 3. Fig. 6 represents a side view of the composite blade and supporting

member. Fig. 7 represents an end view of the same. Fig. 8 represents a section through the blade, the cutting plane being on line 8—8 on Fig. 6. Fig. 9 represents a view of the outer contacting face of the blade. Fig. 10 represents an elevation of one pair of oscillating packing members for said composite blade. Fig. 11 represents an end view of one of said members. Fig. 12 represents a view of the opposite end of said member. Fig. 13 represents a vertical section of the engine, the cutting plane being on line 13—13 on Fig. 2. Fig. 14 represents a section through the inlet pipe and valves, the cutting plane being on line 14—14 on Fig. 3, and Figs. 15 to 24 inclusive represent diagrams of the various cam members for operating the valves.

Similar characters designate like parts throughout the several figures of the drawings.

In the drawings, 10 represents a casing supported by means of feet 11. The casing 10 is provided with a plurality of piston chambers 12 and 13, these piston chambers being cylindrical except between the inlet passage 14 and outlet passage 15, at which point each piston chamber is provided with a depression accurately fitting the periphery of the revoluble pistons 16 and 16* secured to and revoluble with a shaft 17 eccentrically mounted within said piston chambers 12 and 13 and having bearings 18 in the end plates 19 secured by suitable bolts to the casing 10.

The casing 10 is provided with a suitable water jacket 20 through which water is adapted to circulate to keep the casing cooled during the operation of the engine. The shaft 17 is provided with a passage 21 which communicates with a chamber 22 in a non-revoluble sleeve 23 mounted upon one end of the shaft 17, which chamber 22 is connected by a pipe 24 to a pump 25 driven by the gears 26 and 27 by the rotation of said shaft 17.

A water pipe 28 communicates with said pump 25 and when the pump is in operation water is forced into the chamber 22, thence through the passage 21 into the water passage 29 in one of the pistons 16, said water passage 29 also communicating through the passage 30 in the shaft 17 to a similar water passage 29 in the other piston 16*.

A passage 31 in the shaft 17 communicates with the water passage 29 in said pis-

ton 16* and provides an outlet for the water being forced by means of the pump 25 through the passages in said pistons and shaft, thus keeping the pistons and shaft cool during the operation of the engine.

The inner faces of the end plates 19 and the division wall 32 between the piston chambers 12 and 13 are each provided with an annular groove concentric with the main portion of the wall of the piston chambers 12 and 13 and in each of these grooves is mounted a ring 33, each ring 33 being provided with an extension 34 projecting toward each other in pairs. These extensions 34 are each provided with a flange 35 adapted to enter a groove in the inner end of the blade 36 or 36*, said blade being provided, in grooves in either end face, with the contacting members 37 forced outwardly by means of the springs 38 into contact with the inner wall of the end plates 19 and division wall 32.

Each of the end members 37 is provided at its outer end with inwardly extending projections 39 which overlap each other in a groove formed in the outer end of the blade 36 or 36*. Between the extensions 34 and the blade 36 or 36* are springs 40 adapted to force the outer ends of the overlapping projections 39 into contact with the wall of the piston chambers 12 or 13 during the rotation of the pistons 16 and 16* therein. This composite blade formed of different members forced outwardly into contact with the opposing walls of the piston chamber by means of springs, with the various members overlapping one another, provides an effective means of packing the joints between said chamber walls and the piston blade during the operation of the engine.

Within the periphery of each piston 16 and 16* is a depression 41 in which the blade 36 or 36* is adapted to operate. Portions of the side walls of this depression are made cylindrical to receive the divided semi-cylindrical packing members 42, the flat face of which bears against the side walls of said packing member 36-36* and forms a suitable guide therefor which is adapted to oscillate during the rotation of the eccentric pistons 16-16*, thus permitting the blade 36-36* to always remain radial to the central axis of the piston chambers 12 and 13 while the piston 16 is revolvable about the axis of the shaft 17 eccentric to the axis of said piston chambers.

A pinion 43 mounted upon the shaft 17 meshes with a gear 44 revolvable about a fixed stud 45 secured to one of the end plates 19. This gear 44 is provided with a bevel gear 46 which meshes with a similar bevel gear 47 secured in and revolvable with a shaft 48 mounted in bearings 49 projecting from one end of the engine.

65 A bevel gear 50 secured to the upper end

of said shaft 49 meshes with a similar gear 51 mounted upon a shaft 52 in bearings 53 on the upper end of the casing 10, said shaft 52 being parallel with the piston shaft 17. Between the bearings 53 upon the shaft 52 are mounted a plurality of cam members 53*, 54, 55, 56, 57, 59, 60, 62, 63, and 66.

Secured to the casing 10 are brackets 63* supporting a rod 64 on which are mounted the cylindrical hubs 65 and 66*, said hubs 65 and 66* being provided respectively with arms 67 and 69 the free end of each of which is provided with an anti-friction member which is engaged respectively by the cam members 54 and 55 to cause an oscillation of said cylindrical hubs 65 and 66* during the rotation of the cam shaft 52.

The hub 65 is provided with an arm 70 which engages with the stem 71 of an inlet valve 72, said valve being normally closed by means of the spring 73 and opened whenever the projection upon the cam member 54 causes an oscillation of the hub 65 about the rod 64. In a similar manner the hub 66* is provided with an arm which engages with the valve stem 75 of a valve 76 which is adapted to be operated by means of the cam member 55 to admit the motive agent to the piston chamber 13 from the inlet pipe 77, which also supplies the motive agent to the piston chamber 12 when the valve 72 is open.

In the casing 10 and just in advance of the inlet valves 72 and 76 are the spark plugs 78 and 78* of any well-known construction. 100 On the opposite side of the engine, in brackets 79 secured to the casing 10 is a rod 79* on which are mounted semi-cylindrical hubs 80 and 81, these hubs 80 and 81 being provided with arms 82 and 83, the free ends 105 of which are provided with anti-friction members which engage respectively with the cam members 56 and 57 secured to and revolvable with the cam shaft 52.

The hub 80 is provided with an arm 84 engaging with the valve stem 85 of an exhaust valve 86 normally retained in closed position by means of the spring 87 and adapted to be opened during the operation of the engine by the action of the cam projection 115 upon the cam member 56 when in the rotation of the cam shaft 52 such projection causes an oscillation of the hub 80 about the rod 79.

The hub 81 is similarly provided with an 120 arm 88 engaging with the valve stem 89 of the exhaust valve 90 normally closed by means of the spring 91 and adapted to be opened by the cam projections upon the cam member 57 to permit of an exhaust from the piston chamber 13 through the exhaust pipe 92, the valve 86 when opened permitting an exhaust from the piston chamber 12 through the same exhaust pipe 92.

125 The inlet valves 72 and 76 each communi-

cate through the inlet passage 14 with the piston chambers 12 and 13 while the exhaust valves 86 and 90 similarly communicate with the piston chambers 12 and 13 through 5 the exhaust passage 15.

The exhaust passage 15 from the piston chamber 12 also is provided with a valve 93 while the exhaust passage 15 from the piston chamber 13 is provided with a valve 94, 10 these valves 93 and 94 both opening into a chamber 95 in the casing 10, permitting a communication between the piston chambers 12 and 13 whenever the valves 93 and 94 are opened.

15 The valve 93 is normally retained in closed position by the spring 96 and is opened by the lever 97 when operated by means of the cam projection upon the cam member 53* during the rotation of the cam shaft 52. 20 The valve 94 is similarly normally retained in closed position by means of a spring 98 and is opened by the oscillation of the lever 99 when actuated by the cam projections upon the cam member 59 mounted upon the 25 revolute cam shaft 52.

A valve 100 surrounding the stem of the valve 93 and normally retained in closed position by means of the spring 101 is adapted to be opened by the oscillation of the lever 30 102 when actuated by the cam projections on the cam member 60 secured to and revolute with the cam shaft 52, this opening of the valve 100 providing a communication between the chamber 95 and the compression chamber 103 for the piston chamber 12.

A similar valve 104 surrounding the valve stem of the valve 94 is normally retained in closed position by means of a spring 105 and is opened by the oscillation of a lever 40 106 when said lever is actuated by the cam projections upon the cam member 66 secured to and revolute with the cam shaft 52, this opening of the valve 104 providing a communication between the chamber 95 and the compression chamber 103* for the piston chamber 13.

45 40 When said lever is actuated by the cam projections upon the cam member 66 secured to and revolute with the cam shaft 52, this opening of the valve 104 providing a communication between the chamber 95 and the compression chamber 103* for the piston chamber 13. A valve 107 normally closed by means of a spring 108 is adapted, when thus closed, to shut off communication between the compression chamber 103 and 50 the inlet passage 14 of the piston chamber 12, but said valve 107 may be opened by the movement of the lever 109 whenever said lever is actuated by the cam projections on the cam member 62 to permit the contents

55 of the compression chamber 103 to pass into the piston chamber 12 through the inlet passage 14. Similarly a valve 110 normally closed by a spring 111 is adapted to be opened by the oscillation of the lever 112 60 when actuated by the cam projections upon the cam member 63 mounted upon the cam shaft 52 to permit the contents of the compression chamber 103* to pass into the piston chamber 13 through the inlet passage 14.

65 The cooling medium is admitted to the

water jacket 20 through the pipe 113 and after passing through the various chambers and passages constituting this water jacket it passes therefrom through the outlet pipe 114.

The packing members 42 are each provided with a socket in which is mounted a spring 115 which bears against the other packing member to separate the same to take up the wear and always retain the ends of these members against the walls of the 75 piston chambers.

In the position of the various parts as shown in Figs. 3 and 13 of the drawings a charge is supposed to have just been admitted through the valve 72 in advance of 80 the blade 36 in the piston chamber or cylinder 12 and the valve 107 has just been opened to permit a compressed charge within the chamber 103 to be admitted behind the blade 36. At this time the inlet valve 76 85 to the piston chamber or cylinder 13 is open and the explosive mixture is being admitted through the same into said piston chamber 13 and the valve 94 is open admitting the charge in front of the blade 36* to the 90 compartment 95. All of the other valves communicating with the piston chamber 13 are closed as is shown in Fig. 13 of the drawings and the valve 94 closes when the blade 36* reaches the point A'.

95 While the various valves and pistons are in this position (with the blade 36 at E) the spark plug 78 in the chamber 12 is operated to cause an explosion of the explosive mixture behind the blade 36 in said chamber 12 and in the compression chamber 103 and passage 14 between said compression chamber 103 and said piston chamber 12, this explosion driving the piston ahead about the axis of the shaft 17 in the direction of the 105 arrow indicated on Fig. 3 of the drawings.

By the movement of the blade 36 the charge in the piston chamber 12 in advance of said blade 36 is compressed, the valves 86 and 93 being closed until the blade 36 reaches the point F. When the blade 36 reaches the point F the valves 93 and 104 are opened by the cam throws upon their respective operating cams, thus opening up communication between the piston chamber 12 and the compression chamber 103* of the 110 piston chamber 13.

115 The charge contained within the piston chamber 12 in advance of the blade 36 is thus permitted to pass through the exhaust 120 passage 15 and through the chamber 95. The continued rotation of the piston 16 with its blade 36 will cause the charge in advance thereof and that within the chamber 95 and the compression chamber 103* of 125 the piston chamber 13 to be further compressed until the blade 36 reaches the point A, when the valve 93 will be closed and the exhaust valve 86 will be opened, thus permitting that portion of the charge between 130

the blade 36 and the valve 93 in the piston chamber 12 to be carried away through the exhaust pipe 92. In the meantime the inlet valve 76 of the piston chamber 13 having been open, the movement of the blade 36* in the piston 16* about the axis of the shaft 17 has drawn in a fresh charge from the inlet pipe 77 in advance of the blade 36*, which blade in the revolution of the piston 16* will cause a compression of this charge in a similar manner in which the charge in the piston chamber 12 is compressed.

When the blade 36* in the piston chamber 13 reaches the point D' the valve 110 will be opened, permitting the compressed charge within the compression chamber 103* of the piston chamber 13 to pass into said piston chamber in the rear of the blade 36* and when the blade 36* reaches a point E' in said piston chamber the spark plug 78* thereof will cause an explosion and continue the rotation of the piston in the direction of the arrow indicated on Fig. 13 of the drawing.

When the blade 36 reaches the point B the valve 100 is opened and the burnt charge in the chamber 95 is driven out through the compression chamber 103 and passage 14 into the piston chamber 12 in advance of the blade 36 to be discharged therefrom through the exhaust valve 86. When the blade 36 reaches the point C the valve 107 is closed, shutting off further communication between the compression chamber 103 and the piston chamber 12.

When the blade 36 in the piston chamber 12 reaches the point D the valve 107 is again opened opening up communication between the compression chamber 103 and said piston chamber 12, the rotation of the piston in the piston chamber 13 having compressed a charge in said piston chamber and forced it into the compression chamber 103 prior to the opening of this valve 107 and the valve 94 having been closed when the blade 36* reaches the point F'.

When the blade 36 in the piston chamber 12 reaches the point E again at the commencement of the second revolution the valve 100 again closes and the spark plug 78 of that piston chamber operates to cause a second explosion in the piston chamber 12 and as the valve 86 is still open the cylinder or piston chamber is cleared of exhaust. In the meantime the valve 94 closes when the blade 36* in the piston chamber 13 reaches the point A' and at the same time the exhaust valve 90 opens. When the blade 36* reaches the point B' the valve 104 opens and a little later when this same blade reaches the point C' the valve 110 closes, prior to the closing of which valve 110 the compression chamber 103* is cleared from the burnt gases contained therein.

When the blade 36* reaches the point D'

the inlet valve 75 opens into the piston chamber 13 and admits a new charge behind said blade 36*, the valve 104 closing as soon as the blade has reached the point E'. The pistons continue to revolve and when the blade 36 in the chamber 12 reaches the point B the valve 100 opens and as soon as this same blade reaches the point C the valve 107 closes preparatory to receiving another charge in the compression chamber 103. When the blade 36 of the piston chamber 12 reaches the point D the inlet valve 72 opens and a new charge is admitted to the piston chamber 12.

At the commencement of the third revolution when the blade 36 in the chamber 12 reaches the point E the valve 100 again closes and a charge is drawn in to the piston chamber 12. When the blade 36* in the piston chamber 13 reaches the point A' near the commencement of the third revolution the valve 90 closes, and as the valve 104 is still open any charge in advance of the blade is forced into the compression chamber 103 of the piston chamber 12, the valve 94 being opened when the blade 36* reaches the point F', while as the valve 76 still remains open a fresh charge is being drawn into the piston chamber 12 behind the blade 36.

When the blade 36 of the piston chamber 12 reaches the point A the exhaust valve 86 closes and the inlet valve 72 also closes, the valve 100 subsequently opening when the blade 36 reaches the point B, opening up communication between the compartment or chamber 95 and the compression chamber 103.

When the blade 36 in the piston chamber 12 reaches the point D the valve 107 again opens permitting the compressed charge confined in the compression chamber 103 to pass through the inlet passage 14 behind the blade 36 so that when the blade reaches the point E an explosion can take place and the whole operation as described be repeated. It is obvious therefore that in the first revolution of the pistons two explosions take place, one at the commencement of the first cycle in the piston chamber 12, and the second explosion at the commencement of the second cycle in the piston chamber 13, while at the commencement of the third cycle or the second revolution a second explosion occurs in the piston chamber 12. By the operation of the device the charge is readily compressed in one piston chamber and forced into the compression chamber of the other piston chamber preparatory for admission into that piston chamber in the rear of the blade of its respective piston at the proper time for the explosion to take place. Provision is also made to clear burnt gases from the various piston chambers and from the compression chambers before fresh charges are admitted thereto.

The blade 36 may be made up as shown in Fig. 4 of the drawings and as heretofore described, or as shown in Figs. 6, 7, and 8 of the drawings, in which the member 108 is secured to the extensions 34 of the ring 33 by means of screws 109. The member 108 has a groove cut lengthwise thereof in which is positioned a leaf spring 110 bearing against the extensions 39 of the side plates 37, the purpose of this spring being to retain the outer face of the member 39 always in contact with the wall of the cylinder.

In practice in order to have the engine perfectly balanced four piston chambers are usually used, the construction shown in the drawings being duplicated and the explosions in one set being arranged to occur at the commencement of the 4th, 5th, and 6th cycles of the engine.

It is believed that the operation of the invention will be fully understood from the foregoing.

Having thus described my invention, I claim:

1. In a device of the class described, the combination of two cylinders; a piston in each; a compression chamber for each cylinder; a valve between each chamber and its cylinder; a valved passage between said cylinders; a valve between each compression chamber and said passage; a revoluble shaft; and a plurality of cams thereon for operating said valves.
2. In a device of the class described, the combination of two cylinders; a piston in each; a compression chamber for each cylinder; a valve between each chamber and its cylinder; a valved passage between said cylinders; a valve between each compression chamber and said passage; an inlet valve; an exhaust valve; a revoluble shaft; and cams on said revoluble shaft for operating said valves.
3. In a device of the class described, the combination of two cylinders; a piston in each; a passage connecting said cylinders; a valve between said passage and each cylinder; a compression chamber for each cylinder; and outlet valve from each chamber to its cylinder; an inlet valve to each chamber from said passage; and means for operating said valves to permit compressing alternately in each cylinder and then admitting the compressed mixture to the compression chamber of the opposite cylinder.
4. In a device of the class described, the combination of two cylinders; a piston in each; a passage connecting said cylinders; a valve between said passage and each cylinder; a compression chamber for each cylinder; an outlet valve from each chamber to its cylinder; an inlet valve to each chamber from said passage; means for operating a valve between said cylinder and passage

when the piston has reached a predetermined point; means for opening the inlet valve to the compression chamber of the other cylinder; and means for operating the outlet valve of said compression chamber of the other cylinder at a predetermined time and admitting to said cylinder a compressed charge.

5. In a device of the class described, the combination of two cylinders; a piston in each; a passage connecting said cylinders; a valve between said passage and each cylinder; a compression chamber for each cylinder; an outlet valve from each chamber to its cylinder; an inlet valve to each chamber from said passage; means for operating a valve between said cylinder and passage when the piston has reached a predetermined point; means for opening the inlet valve to the compression chamber of the other cylinder; means for operating the outlet valve of said compression chamber of the other cylinder at a predetermined time; and means for exploding the compressed charge thus admitted.

6. In a device of the class described, the combination of two cylinders; a piston in each; a passage connecting said cylinders; a valve between said passage and each cylinder; a compression chamber for each cylinder; an outlet valve from each chamber to its cylinder; an inlet valve to each chamber from said passage; means for operating a valve between said cylinder and passage when the piston has reached a predetermined point; means for opening the inlet valve to the compression chamber of the other cylinder; means for operating the outlet valve of said compression chamber of the other cylinder at a predetermined time; means for exploding the compressed charge thus admitted; and means for opening the exhaust valve from said cylinder when the piston blade reaches the passage thereto.

7. In a device of the class described, the combination of two cylinders; pistons therein oppositely disposed; means for admitting a fresh charge in advance of one of the pistons; a compressed explosive mixture behind said pistons; means for exploding said compressed charge and thereby revolving the piston and effecting a compression of the fresh charge in advance thereof; means for admitting the charge thus compressed to the other cylinder behind its piston; means for admitting a fresh charge into the other cylinder ahead of said piston; means for exploding the compressed charge in the other cylinder and causing the compression of the fresh charge therein ahead of said piston; means for admitting said charge thus compressed into the first-mentioned cylinder; and means for exploding said compressed charge.

8. In a device of the class described, the

combination of two cylinders; pistons there-
in oppositely disposed; means for admitting
a fresh charge in advance of one of the pis-
tons; a compressed explosive mixture be-
hind said pistons; means for exploding said
compressed charge and thereby revolving
the piston and effecting a compression of
the fresh charge in advance thereof; means
for admitting the charge thus compressed to
10 the other cylinder behind its piston; means
for admitting a fresh charge into the other
cylinder ahead of said piston; means for
exploding the compressed charge in the other
cylinder and causing the compression of the
15 fresh charge therein ahead of said piston;
means for admitting said charge thus com-
pressed into the first-mentioned cylinder;
means for exploding said compressed charge;
and means for successively scavenging the
20 cylinders after the explosions have occurred.

9. In a device of the class described, the
combination of two cylinders; pistons there-
in oppositely disposed; a compression cham-
ber for each cylinder; means for admitting
25 a fresh charge into one of said cylinders in
advance of its piston; means for admitting
from its compression chamber a compressed
charge behind said piston; means for ex-
ploding said compressed charge and there-
30 by revolving the piston and effecting a com-
pression of the fresh charge in advance
thereof; means for admitting a fresh charge
into the other cylinder in advance of its
piston; means for admitting the compressed
35 charge in the first-mentioned cylinder into
the compression chamber of the other cylin-
der; means for admitting the compressed
charge in said chamber to the other cylin-
der behind its piston; means for exploding
40 said compressed charge in the other cylin-
der and thereby compressing the charge in
front of its piston; means for admitting the
charge thus compressed into the first-ment-
ioned compression chamber; means for ad-
45 mitting said compressed charge into the
first-mentioned cylinder behind its piston;
and means for exploding this charge.

10. In a device of the class described, the
combination of two cylinders; pistons there-
50 in oppositely disposed; a compression cham-
ber for each cylinder; means for admitting
a fresh charge into one of said cylinders in
advance of its piston; means for admitting
from its compression chamber a compressed
55 charge behind said piston; means for ex-
ploding said compressed charge and thereby
revolving the piston and effecting a com-
pression of the fresh charge in advance
thereof; means for admitting a fresh charge
60 into the other cylinder in advance of its
piston; means for admitting the compressed
charge in the first-mentioned cylinder into
the compression chamber of the other cylin-
der; means for admitting the compressed

charge in said chamber to the other cylinder 65
behind its piston; means for exploding said
compressed charge in the other cylinder and
thereby compressing the charge in front of
its piston; means for admitting the charge
thus compressed into the first-mentioned com-
70 pression chamber; means for admitting said
compressed charge into the first-mentioned
cylinder behind its piston; means for ex-
ploding this charge; and means for suc-
cessively scavenging the cylinders and com-
75 pression chambers after the explosions have
occurred.

11. In a device of the class described, the
combination of a cylinder; a revoluble pis-
ton eccentrically mounted therein and pro-
80 vided with a chamber extending to its pe-
riphery; a revoluble ring in each side wall
of said cylinder and concentric therewith;
and a blade mounted thereon and positioned
in said peripheral chamber in said piston. 85

12. In a device of the class described, the
combination of a cylinder; a revoluble pis-
ton eccentrically mounted therein and pro-
90 vided with a chamber extending to its pe-
riphery; a revoluble ring in each side wall
of said cylinder and concentric therewith;
a blade mounted thereon and positioned in
said peripheral chamber in said piston; and
means between said ring and blade for forc-
ing the outer end of the latter into contact 95
with the cylindrical wall of said cylinder.

13. In a device of the class described, the
combination of a cylinder; a revoluble pis-
ton eccentrically mounted therein and pro-
100 vided with a chamber extending to its pe-
riphery; a revoluble ring in each side wall
of said cylinder and concentric therewith;
a blade mounted thereon and positioned in
said peripheral chamber in said piston; side
members on said blade provided with over-
lapping extensions in a groove in the outer
end of said blade; and means for forcing
said side members into contact with the side
walls of said cylinder. 105

14. In a device of the class described, the 110
combination of a cylinder; a revoluble pis-
ton eccentrically mounted therein and pro-
vided with a peripheral chamber a portion
of the walls of which are cylindrical; oscil-
115 lating members therein; a blade mounted
between said oscillating members; means for
forcing said blade outwardly; and revoluble
rings embedded in annular grooves in the
side walls of the cylinder and concentric
120 therewith having projections thereon form-
ing a support for the inner end of said
blade.

Signed by me at 4 Post Office Sq., Boston,
Mass., this 15th day of July, 1909.

HERBERT I. WILBER.
